UNITED STATES PATENT OFFICE.

WALTER KOEGER, OF ALEXANDRIA, MISSOURI.

SAWING ATTACHMENT FOR TRACTORS.

Application filed April 14, 1924. Serial No. 706,481.

To all whom it may concern:

Be it known that I, WALTER KOEGER, a citizen of the United States, residing at Alexandria, in the county of Clark and

State of Missouri, have invented a new and useful Sawing Attachment for Tractors, of which the following is a specification.

This invention relates to a sawing attachment for tractors and is designed primarily for use in connection with the well known Fordson tractor although it is to be understood that by making certain modifications in structure, it may be applied to tractors of other types.

15 The object of the invention is to provide a simple and efficient inexpensive structure that can be applied readily and is designed more especially for use in cutting cord wood, kindling, etc.

20 Another object is to provide efficient means whereby the wood can be fed to the saw.

A further object is to utilize bolts already in position on the tractor for attaching the 25 device to the machine.

With the foregoing and other objects in view which will appear as the description proceeds, the invention resides in the combination and arrangement of parts and in 30 the details of construction hereinafter described and claimed, it being understood that changes in the precise embodiment of the invention herein disclosed may be made within the scope of what is claimed without departing from the spirit of the 35 invention.

In the accompanying drawings the preferred form of the invention has been shown.

40 In said drawings—

Figure 1 is a side elevation of the attachment, a portion of the tractor to which it is applied being indicated by broken lines.

Fig. 2 is a plan view of the attachment.

45 Fig. 3 is an elevation of the side of the attachment opposite to that shown in Fig. 1.

Fig. 4 is an end elevation.

Referring to the figures by characters of 50 reference 1 designates side members which are provided at one end with an attaching strip 2 the upper and lower ends of which are adapted to be bolted to the tractor T as shown at 3. The forward portions of the side members are supported by braces 4 bolted thereto and to the top portion of

the tractor as shown, these braces being preferably inclined downwardly and forwardly. A cross strip 5 is secured to the forward end portions of the side members 60 1 and has bearings 6 in which is journaled a shaft 7. One end of this shaft carries a pulley 8 while the other end is engaged by a circular saw 9. This saw can be removed when not in use and mounted on a stud 10 65 projecting laterally from the rear end portion of one of the side members 1 as shown in Figs. 2 and 3.

Secured to the braces 4 at the pulley side of the attachment is an arm 11 carrying an 70 arcuate shield 12 supported concentric with the pulleys 8 and another arm 13 is pivotally connected to said braces 4 and carries an idler pulley 14. A tractor of the Fordson type is ordinarily provided with the pulley 75 P on which a belt B can be placed, this being shown in Fig. 1. The belt B is adapted to be extended under the idler 14 and engage the pulley, idler 14 serving as a tightener, it resting by gravity on the belt. 80

The side member 1 at the saw side of the attachment has a bracket 15 to which is connected an arcuate shield 16 lapping the back portion of the periphery of the saw as shown in Fig. 3. This shield is also preferably 85 connected to one of the braces 4 by means of a bracket 17.

Secured to the side members 1 below the braces 4 are hangers 18 substantially L-shaped, the lower arms 19 being extended 90 forwardly and being connected by braces 20 extending upwardly and attached to the side members 1. When the attachment is in position on the tractor the hangers 18 extend in front of and bear backwardly 95 against the front axle A as shown in Fig. 1.

The arms 19 are connected at their front ends by a cross member 21 which can be integral therewith if desired. To this member is attached a bracket 22 constituting a 100 bearing for the shank 23 of a crank arm 24 used in starting the engine of the tractor.

Pivottally connected to the front end portion of the arms 19 is a frame made up of angle strips 25, 26 and 27. The angle strip 105 25 is located adjacent one of the arms 19 while angle strips 26 and 27 extend to opposite sides of the other arm 19 and are fixedly connected in any suitable manner so as to swing in unison although spaced apart. The angle strips 25 and 26 are connected by 110 cross strips 28 so that all of the strips will

swing together about their pivotal connections with the arms 19. The upper ends of the strips 25, 26 and 27 are bent forwardly at obtuse angles as shown at 29 and secured to the strips 26 and 27 at the angles formed therein is a yoke 30 diverging upwardly from the said strips. The upper or intermediate portion of the yoke is offset forwardly and downwardly as shown at 31 and is adapted to receive the upper end of the leaf spring 32, the lower portion of which is attached to the strips 26 and 27. This spring constitutes a shield so that the hand of a person gripping the intermediate portion 31, which constitutes a handle, will be prevented from coming against the saw.

An arm 33 is attached to the upper portion of the strip 25 at the angle thereof and as shown particularly in Fig. 1, this arm as well as the yoke 31 cooperating with the obtuse portions 29 to provide a wood receiving cradle, whereby the wood to be cut will be supported transversely of the plane of the saw 9.

A chain 34 or the like can be used for limiting the forward swinging of the frame made up of strips 25, 26 and 27 and their connections.

In using this structure the saw 9 is set in motion after which the wood to be cut is placed in the cradle formed by the angle portions 29, the yoke 30 and the arm 33. The operator grasping the handle 31, then swings the cradle toward the saw, so that the saw will be received between the upper portions of the strips 26 and 27 and cut into the wood. The saw will also be received between the sides of the yoke 30 and this forward movement of the cradle will continue until the upper ends of the strips 25, 26 and 27 come against the bearings of the shaft 7 and thus brought to a stop. It will be obvious that after the cradle is moved past the center of gravity the weight thereof and of the load thereon will be sufficient to continue to feed the wood against the saw so that the handle 31 can be released. However, there is no danger of injury to the hand because the spring 32 will act as a guard as will be apparent by referring to Figs. 2 and 4.

It will be noted that this attachment will not interfere with the movements of the tractor to which it is applied and importance is attached to the fact that the axle of the tractor is utilized as an abutment to assist the braces in supporting the attachment in proper position.

What is claimed is:

1. An attachment of the class described including connected side members and hangers, a shaft journaled on the side members, a saw carried thereby, connected members

pivotaly mounted on the hangers and having their upper end portions disposed at an angle, a yoke connected to one of the members and cooperating with the angle portions of the members to form a work holding cradle, a portion of the yoke constituting the handle, said yoke being adapted to receive a portion of the saw during the sawing operation, and a shield carried by the cradle and projecting through the yoke between the handle portion thereof and the saw.

2. An attachment for tractors including connected side members and hangers, a saw mounted for rotation, a cradle pivotally connected to the hangers and including spaced strips and a yoke connecting the strips, said yoke being adapted to receive the saw therein during the sawing operation, a portion of the yoke constituting the handle, a shield connected to the cradle and extending through the yoke between the saw and the handle portion, and flexible means for limiting the movement of the cradle away from the saw, said cradle being movable by gravity toward the saw during the completion of each sawing operation.

3. An attachment for tractors including a shaft, a saw thereon, means for supporting the shaft transversely of the tractor, hangers fixed relative to the supporting means and having forwardly extending portions, a frame pivotally connected to said portions and including spaced strips for receiving the saw therebetween, an upstanding yoke connecting the strips for receiving the saw therebetween, a portion of the yoke constituting the handle, and a guard connected to said strips and extending through the yoke between the saw and the handle portion.

4. An attachment for tractors including a shaft, a saw thereon, means for supporting the shaft transversely of the tractor, hangers fixed relative to the supporting means and having forwardly extending portions, a frame pivotally connected to said portions and including spaced strips for receiving the saw therebetween, an upstanding yoke connecting the strips for receiving the saw therebetween, a portion of the yoke constituting the handle, a guard connected to said strips, and extending through the yoke between the saw and the handle portion, means for limiting the movement of the frame away from the saw and means cooperating with the free ends of the strip for limiting the movement of the frame toward the saw.

In testimony that I claim the foregoing as my own, I have hereto affixed my signature in the presence of two witnesses.

WALTER KOEGER.
